2 SHEETS—SHEET 2.

UNITED STATES PATENT OFFICE.

FRANK W. BURPEE, OF BELLINGHAM, WASHINGTON.

COATING-MACHINE.

1,099,840.

Specification of Letters Patent. Patented June 9, 1914.

Application filed August 2, 1911. Serial No. 641,940.

To all whom it may concern:

Be it known that I, FRANK W. BURPEE, a subject of the King of Great Britain, and a resident of the city of Bellingham, in the county of Whatcom and State of Washington, have invented certain new and useful Improvements in Coating-Machines, of which the following is a specification.

The present invention pertains to a continuous machine of the above type primarily devised for coating paper receptacles with paraffin to render them impervious to liquid.

The primary aim of the invention is the provision of automatic apparatus capable of presenting receptacles progressively in different angular positions for coating, dripping and delivery.

With reference to the accompanying drawings, wherein similar reference characters designate corresponding parts throughout the several views: Figure 1 is a side elevation of a machine embodying the features of my invention in such form as now preferred by me, parts being broken away. Fig. 2 is a plan of the same with portions of some of the parts broken away. Fig. 3 is a vertical transverse section on line 3—3 of Fig. 1. Fig. 4 is a side elevation illustrating fragmentarily the carrier, the guides or track and the provision for removing the coated receptacles from the carrier, and Fig. 5 is a horizontal section on line 5—5 of Fig. 4.

The invention embraces work supporting mechanism appropriately designed for advancing receptacles sidewise for coating and subsequently upending them for dripping and finally inverting them for delivery.

In the present embodiment I have shown work holders 2, of preferred form for supporting tapered receptacles or bottles, as 1, combined with a carrier in the form of a swivel link belt 3 which extends about guiding sprocket wheels 4, 4' and 5 with a portion of its upper run sagging in an elevated tank 6 between driving sprocket wheels 7, 7', fixed to shafts 7', 7' which are journaled on the tank and connected by link belt gearing 8.

Connected by spur gearing 7'' with one of the shafts 7' is a shaft 9 which is journaled on tank 6 and provided with a drive pulley 9' to which power is applied to operate belt 3 in the direction indicated by the arrow in Fig. 1.

The holders 2, which are designed to re-

ceive receptacles 1 sidewise, each comprise concaved side seats 20, 21, secured to respective end portions of a base 22 and provided with inwardly projecting flanges 20', 21' which serve as end guards to hold the receptacle seated in the holder from endwise displacement. In this connection it will be observed that the base parts of the holders extend crosswise of and are secured to respective link sections of belt 3 in alternate arrangement with swivel coupling sections 3' which permit of angular adjustment of the holders to upend the receptacles.

Tank 6 is equipped with a receptacle guiding device comprising circular members 11, 11', secured to a shaft 12 which is positioned between the wheels 7 and journaled on the tank in concentric relation with depending semicircular guides or tracks 13, 13' disposed at opposite sides of belt 3 for guiding engagement with opposite angular lugs 23 of the holders 2 and extending into angular approach and delivery guide sections 13', 13'' which are secured to respective brackets 10 of tank 6.

The receptacles 1 are placed in the holders advancing along the approach guide sections 13' and thence carried along the guide sections 13 in engagement with the rotatable members 11, 11' which retain the receptacles in the holders during their immersion in a body of paraffin, as C, contained in tank 6 and maintained, as will be later understood, in a fluid state.

Extending from the guide sections 13'' are quarter turn spiral guide sections 3^a, 4^a adapted to upend the holders advancing from the tank and connected, respectively, with horizontal guide sections 3^b, 4^b, which extend over an inclined trough part 6' of tank 6 and serve to guide the holders in upended position with the receptacles mouth down for dripping.

Extending from the guide sections 3^b, 4^b and secured to fixed brackets 10' are half turn, spiral guide sections 3^c, 4^c adapted to invert the holders advancing from trough 6' and connected, respectively, with horizontal guide sections 3^d, 4^d. These guide sections 3^d, 4^d which serve to guide the holders with the receptacles bottom down for delivery, are provided with quarter turn spiral terminations 3^e, 4^e for guiding the empty holders to horizontal position.

15 designates a curved deflector secured to a bar extension 15' of trough 6' and posi-

tioned between the guide sections 3^a, 4^a in the path of the holders 2 for directing the receptacles therefrom for delivery to a conveyer 16, comprising a link belt extending 5 alongside bar 15' in parallel arrangement with elevated side guides 17, 17' and taking about sprocket wheels 18, 18".

Conveyer 16 is conveniently driven through the medium of a link belt 16' applied to suitable sprocket wheels secured to shafts 18', 4" which are journaled, in fixed connection with the wheels 18, 4 respectively, on a bracket 19' supported in common with the journal bearing 19" of wheel 4', on a 15 standard 19.

Combined with tank 6 is a chamber 6" provided with a drain cock 24 and containing a pipe coil 25 which is connected through circulating pipes 26, 26' with a 20 water heater, not shown, carrying water at suitable temperature to maintain the paraffin in tank 6 at a proper temperature for coating.

Positioned beneath the lower run of belt 25 3 is an auxiliary steam heating appliance in the form of a pipe coil 28 which is connected with a generator, not shown, to be served with steam at suitable temperature to maintain a heated zone about the belt of 30 sufficient intensity to clear the holders 2 of coating material as they pass between the wheels 4', 5 in guiding engagement with a plate or strip 29 which is supported with coil 28 on cross pieces fixed to the legs of 35 tank 6, as clearly shown.

Having thus described my invention, what I claim as new, and desire to secure by Letters Patent of the United States of America, is:—

40 1. In a machine of the character described, a carrier provided with an adjustable work holder, means whereby the work conveyed on said carrier is coated, means for adjusting the work holder of said carrier 45 to upend the work subsequently to the coating thereof, a delivery conveyer, and means for deflecting the upended work to said conveyer.

2. A coating machine comprising a carrier supported for movement, an angularly movable holder for supporting an open ended receptacle on its side on said carrier, said holder comprising spaced end seats of 50 open form to permit of the passage of coating material therethrough into the ends of the receptacle held thereby, means in the path of said carrier for supporting coating material, and means for moving said holder to upend the receptacle subsequently 55 to the coating operation.

3. A coating machine comprising a carrier supported for movement, an angularly movable holder for supporting an open ended receptacle on its side on said carrier, said holder comprising spaced end seats open at 60 one side for insertion and removal of the work, said end seats being also of open form to permit of the passage of coating material therethrough into the ends of the receptacle held thereby, means in the path of 70 said carrier for supporting coating material, means for moving said holder to upend the receptacle subsequently to the coating operation, and means for removing the receptacle from said holder when said receptacle is in an upright position.

4. In a machine for coating receptacles, means for coating a receptacle, a movably supported carrier provided with movable means for holding a receptacle in horizontal position crosswise of the line of travel for coating, comprising spaced end seats of 80 open form adapted for reception of respective end portions of the work and means for moving said holding means to upend and 85 subsequently invert its receptacle.

5. In a machine for coating open receptacles, a tank for holding coating material, a carrier supported for movement through said tank, a movable holder on said carrier having seats of open form spaced laterally of the carrier for reception of opposite end portions of a receptacle, and means for moving said holder to hold its receptacle 90 on its side during movement through said tank and first on one end and then on the other subsequently to the coating operation.

6. In a machine for coating receptacles, a tank for coating material, a carrier supported for movement through said tank, means 100 on said carrier for holding a receptacle with its end portions at opposite sides of the plane of said carrier, said last named means including spaced seats for the end portions of the receptacle and being movable to position a receptacle in upright position with respect to said carrier, means for moving said holding means subsequently to the coating operation, and means arranged alongside the path of said carrier adapted to project between the seats of said receptacle holding means for removing a receptacle 105 from the carrier.

Signed at Bellingham, Wash., this 21st day of June, 1911.

FRANK W. BURPEE.
